P. R. FINCH

ROTARY PUMP

Original Filed Dec. 27, 1923

by Earl M. Sinclair Atty

UNITED STATES PATENT OFFICE.

PAUL R. FINCH, OF DES MOINES, IOWA, ASSIGNOR TO ALVAH C. WHITE, OF DES MOINES, IOWA.

ROTARY PUMP.

Original application filed December 27, 1923, Serial No. 682,873, and in Canada August 22, 1925. Divided and this application filed July 17, 1926. Serial No. 123,181.

The subject matter of this invention was originally included in but has been divided from my application filed December 27, 1923, Serial Number 682,873.

55

5 The object of the present invention is to provide an improved construction for a rotary compressor or pump.

A further object is to provide an improved 10 compressor chamber divided into two compartments by means including a hinged plate having slideable connections with an impeller and engaging a wall of the chamber.

15 A further object is to provide an improved construction for a compressor having a rotary or oscillating impeller and having efficient means, so arranged as to prevent leakage, for bridging the space between the impeller and the wall of a chamber whereby 20 said chamber is divided into two separate compartments.

With these and other objects in view, my invention consists in the construction, arrangement and combination of elements 25 hereinafter set forth, pointed out in the claims and illustrated by the accompanying drawing, in which—

Figure 1 is a side elevation, partly in section, showing a double or two-stage compressor embodying my invention.

Figure 2 is a cross-section on the line 2—2 of Figure 1.

Figure 3 is a detail section on the line 3—3 of Figure 2.

35 In the construction of the device as shown in Figures 1, 2 and 3 the numeral 10 designates generally a casing having end plates 11, 12 secured to its walls by means of bolts 13. The casing 10 is formed with a substantially cylindrical chamber 14 and a chamber 15 communicating therewith by means of a passage 16 extending from end to end of said chambers. The chamber 15 has one wall formed on an irregular curve or on an arc of 45 a circle of considerably greater diameter than that of the chamber 14 and merging into the wall of the latter, the partition 17 between said chambers being formed on curves and terminating short of the larger arc of the chamber 15 to produce the passage 50 16. As shown, the chamber 14 is at the top of the casing and the chamber 15 at its base, but the position may be reversed or the com-

pressor placed in any suitable position for operation.

55

The compressor may be formed with double casings of like character and arrangement as is specifically illustrated in Figure 1, to produce a double stage compressor, but I do not wish to be understood as limiting myself to this construction, and will first proceed to describe my invention as if it embodied the single stage compressor.

A shaft 18 is mounted longitudinally and axially of the chamber 14, is journaled for 65 rotation in bearings 19 and 20 in the end plates 11 and 12, projects therefrom and is provided with one or more belt or fly wheels such as 21 at its ends. In the single stage type there are preferably two of the fly 70 wheels 21, one at each end of the shaft, in order to properly balance the moving parts.

An impeller is provided and it has a substantially cylindrical portion 22 of less diameter than the chamber 14 and mounted 75 therein, and is formed with a central longitudinal bore 23 through which the shaft 18 extends loosely. Formed on or fixed to the shaft 18 are one or more eccentrics 24 fitting the bore of the impeller 22, and said eccentrics serve to hold the impeller eccentrically of the chamber 14 and to give it a circular orbital movement therein, in contact with the chamber walls, when the shaft is rotated.

The eccentrics may be of any desired number and fill any desired portion of the length of the bore of the impeller, one only of said eccentrics being shown, in Figure 2. The cylindrical impeller head 22 is formed with a relatively long impeller blade 25 having 90 one margin formed on a curve or arc conforming somewhat to that of the inner wall of the chamber 15 and where it merges or blends into the wall of the chamber 14. However, either the outer surface of the 95 blade 25, or the adjacent wall of the chamber 15, must be formed on a slightly irregular curve in order that the moving contact may be maintained at all times as the impeller is oscillated. The impeller blade 25, it 100 will be understood, projects through the passage 16 and its major portion is within the chamber 15.

The impeller blade 25 terminates in a flange 26 arranged in a position substantially radially of the chamber 15. A rock-

ing partition member 27, formed with trunnions 28, is journaled in the terminal portion of the chamber 15 and is engaged slidably by clamping plates 29 and 30 arranged 5 on opposite sides thereof and spaced apart at their upper margins by spacing blocks 31, and secured to the flange 26 by means of bolts or screws 32 extending through said blocks. Other bolts or screws 33 may be 10 provided extending through the plates 29 and 30 and into the flange 26 and passing loosely through slots 34 in the movable partition 27 to permit sliding movement of said clamping plates and said bolts or screws 15 relative to said partition plate.

Communication ports 35 and 36 are provided for the chamber 15, opening thereto from opposite sides of the partition formed therein by the impeller blade 25, the plates 20 29 and 30 and the partition plate 27, which partition plate has a rocking contact with the wall of the said chamber 15.

In practical use the compressor may be driven by any desired means and as the 25 shaft 18 is rotated the cams or eccentrics 24 thereon cause the impeller to revolve in its orbit, having a moving contact at changing 30 points of its periphery with the periphery of the chambers 14 and 15, and such rotation 35 may be in either direction. Assuming that the shaft 18 is rotated counterclockwise, the point of close contact of the impeller with the casing also moves counterclockwise, and the curved blade 25 is lowered at the point *a* 40 into close contact with the inner wall of the chamber 15 at the point *b*, in which position the point *c* of the impeller head 22 is also in close contact with the wall of the chamber 14 at point *d*, and the intake port 36 45 is closed. The charge drawn into the casing by this movement will be trapped within the chamber 15 because of the close contact at two points as above referred to. As the 50 counterclockwise oscillation continues, the two points of contact move in the same direction until the blade 25 contacts at point *e* with the wall of chamber 15 at point *f* and the impeller 22 contacts at point *g* with the wall of chamber 14 at point *h* or adjacent 55 the opening 16. It will be observed that the size of the trapped portion between the points *a*—*b* and *c*—*d* is greater than that of the last described portion between the points *e*—*f* and *g*—*h* owing to the difference 60 of radii of the curves of casing 10, impeller 22 and blade 25, so that the volume of the charge is reduced during such movement. A further counterclockwise movement of the impeller will then act to discharge the 65 trapped charge directly through the passage 16 and the exhaust port 35. It will also be observed that in such counterclockwise movement, a portion of the chamber 15 between the point of contact of blade 25 and wall of the chamber and the intake port 36 will be

enlarged, thus acting to draw in a new charge. The movement is continued until the parts are in the position shown in Figure 2, which constitutes a complete cycle, and it will be seen that at all times some 70 point of impeller 22 or blade 25 will have close contact with some point of the wall of casing 10, and a part of the time there is double contact; and at no time will there be an open passage between the ports 35 and 75 36. Thus a high pressure, or vacuum, is at no time permitted to flash from one of said ports to the other. This insures minimum loss of volume and more silent operation.

It is to be understood that the device may 80 also be operated in a clockwise direction, the difference being that the volume of the trapped charge will tend to be increased throughout certain arcs of movement instead of reduced; and throughout other arcs 85 of movement the charge will be discharged directly through the port 36.

The passage 16 is of sufficient width to 90 permit the described oscillation of the impeller blade 25 without contact with the partition 17, and the movement of the blade causes a corresponding movement of the clamping plates 29 and 30, which slide on the partition plate 27, causing it to rock on its trunnions 28, at all times maintaining 95 a contact at its lower margin, which preferably is rounded, with the adjacent wall of the chamber 15. The clamping plates and partition plate also extend from end to end of the chamber and have a working contact 100 with the end walls of the housing such that comparatively little leakage of fluid can occur.

When it is desired to employ this construction in a two-stage compressor as specifically 105 shown in Figure 1, two similar housings 10 and 10' are employed which are arranged in like position. The housings 10 and 10' are separated in this instance by a relatively 110 heavy partition or common intermediate wall 37, having bearings such as 38 for the trunnions 28 of the partition plates 27 and also having bearings (not shown) for the inner ends of the shafts 18. The two casings 10 and 10' are formed with similar chambers, impellers, impeller blades and partition plates as previously described, and these 115 members are arranged in like relation in the two casings. The exhaust port 35 of the first chamber 10 is closed as by means of a plug 39, and the intake port 36 of the second casing is similarly closed by means of a plug 40, so that the two may be caused to operate together. Communication is provided between the two casings by means of a passage 120 41 formed longitudinally in the central plate 37 and having a port 42 extending laterally to the exhaust portion of the casing 10 and a port 43 extending laterally to the intake portion of the chamber 10'. By this means 125 130

the compressed charge from the casing 10 or first stage compressor is passed on to the casing 10' or second stage compressor and there further compressed and discharged 5 through the outlet port 35 of said casing. The second stage compressor is of less capacity than the first, which may be accomplished by making the casing 10' of less length than the first casing 10, as shown in 10 Figure 1, or by increasing the size of the impeller in the second casing, or both. In either event the impeller of the second stage compressor has less centrifugal force in operation than that of the first and as they 15 have their eccentrics oppositely arranged, said second impeller only partially counterbalances the first impeller; the difference in counterbalancing being accomplished by a fly wheel 21 at one end of the device, and 20 it is possible to omit the fly wheel at the other end, which would have to be employed in the case of a single stage compressor.

The device is provided with suitable gaskets such as 44 between the several casings 25 and partitions or end plates, and said casings are also provided with circumferential ribs or flanges 45 which serve to strengthen and reenforce them and also provide seats for the connecting bolts 13.

30 In connection with the showing in Figure 2, it will be understood that when the device is used as a single stage compressor, the ports 42 and 43 will not occur but end plates like 11 and 12 will be used at the ends of 35 the single casing 10.

I claim as my invention—

1. A compressor comprising a substantially cylindrical chamber, a second chamber communicating with the first and having intake 40 and exhaust ports, an eccentrically movable, substantially cylindrical impeller within the cylindrical chamber having traveling contact with the wall of the latter, a curved blade projecting from the impeller and extending 45 into the second chamber, a partition plate mounted for rocking movement in the second chamber and having one margin rounded and in contact with a wall of said chamber between the intake and exhaust ports, and slidable connections between said partition plate and the free end of said curved 50 blade.

2. A compressor comprising a casing having a substantially cylindrical chamber, a substantially cylindrical impeller eccentrically 55 mounted for oscillatory movement in said chamber, said casing having another chamber communicating with the first and having one wall formed on a curve, and an impeller blade on said impeller projecting within the last-named chamber and having a curved 60 wall adjacent the curved wall thereof, one of the last-named walls being formed on an irregular curve and the other on an arc of a circle. 65

3. A compressor comprising a casing, an impeller mounted for oscillatory movement therein, partitioning means between said impeller and casing wall, the inner wall of the casing and the periphery of the impeller 70 each being formed on a plurality of curves of different radii whereby there is always one or more points of close moving contact of said periphery with said wall.

4. A compressor comprising a casing, an 75 impeller mounted for oscillatory movement therein, partitioning means between one portion of said impeller and the wall of the casing, the inner wall of the casing being formed on a plurality of curves, and a crank 80 or cam shaft mounted for rotation concentrically of one portion of said inner wall and eccentrically of another portion thereof, said impeller being formed with a bearing for said shaft which is located concentrically 85 with respect to one portion of the periphery of said impeller, another portion of said periphery being formed on an irregular curve.

5. A double stage compressor comprising 90 two casings, a shaft extending through and journaled in both of said casings, an impeller mounted for oscillation on said shaft in each of said casings and in opposition to each other, one of said casings being of 95 greater capacity than the other and the impeller therein consequently having less centrifugal force in operation than that in the casing of greater capacity, whereby the lesser impeller partially counterbalances the other 100 impeller, and a fly wheel on said shaft outside the casings completing the counterbalancing of the greater impeller.

PAUL R. FINCH.
